ICE-CUBE DISPENSING MACHINE

Frederick A. Hurley, Miami, Fla.

Application October 8, 1948, Serial No. 53,407

13 Claims. (Cl. 62—108.5)

1

The present invention relates to improvements in ice cube dispensing machines, and has for an object to provide a machine for freezing and delivering ice in cube or other form in adequate quantities directly to drinking glasses or other containers, more particularly for use in the home, in bars, restaurants, drug stores and the like places where iced beverages are apt to be mixed and served.

It is another object of the invention to provide an ice cube dispensing machine so compactly constructed and arranged as to admit of its inclusion in a home or other electric refrigerator without interfering with the normal service of such refrigerator, and in which delivery of the ice cubes is had without requiring the opening of the general refrigerator door.

A further object of the invention resides in providing an ice cube dispensing machine incorporated into a refrigerator or other housing having an ice cube delivery door which on opening controls the delivery of one or more ice cubes, without handling, directly to a receptacle held in front of the door, and in which the door acts as the controlling member for one or more electric switches designed to set in motion the machinery by which water is delivered to movable cups or containers in which the water is subsequently frozen into the ice cubes, advanced through the machine to an exit point and there delivered to a delivery chute by which the formed and frozen ice cubes are directed to and through the open dispensing door and into the receptacle held in the hand of the operator below such dispensing door.

The invention has for its further objects and purposes the provision of a combined conveyor and freezing chamber with means to advance the ice cube receptacles carried by the conveyor in a step by step motion through such freezing chamber from an origin point where an automatic mechanism delivers precooled water to the receptacles to a delivery point where the ice cubes are loosened from the walls of the receptacles and eventually pinched out of the receptacles to the delivery chute, in the provision of a novel form of motor by which the conveyor is given this step by step actuating movement, and in the provision of an improved electric arrangement by which solenoids are controlled for actuating in a proper sequence and timed relationship the delivery of the precooled water to the conveyor cube receptacles and the intermittent actuation of the conveyor.

With the foregoing and other objects in view

2

the invention will be hereinafter more fully described and more particularly pointed out in the appended claims.

In the drawings in which like or corresponding parts are denoted by the same reference characters throughout the several views—

Figure 1 is a fragmentary vertical sectional view taken through a refrigerator structure showing one form of ice cube dispensing machine constructed according to the present invention.

Figure 2 is a vertical section taken on an enlarged scale through the water delivery mechanism.

Figure 3 is a side elevational view of the ice cube container conveyor showing the ejecting device, delivery chute and dispensing door in section.

Figure 4 is a top plan view of a form of conveyor employed.

Figure 5 is a fragmentary longitudinal section through a portion of the conveyor showing a form of ice cube container.

Figure 6 is a perspective view of a pyramidal form of ice cube container.

Figure 7 is a similar view of a frusto-conical form of ice cube container.

Figure 8 is a circuit diagram showing one arrangement for actuating the various devices in a predetermined sequence of a selected cycle of operations.

Figure 9 is an end elevational view of the conveyor.

Figure 10 is an end elevational view of the ejecting and delivery mechanism taken on the line 10—10 in Figure 3.

Figure 11 is a transverse sectional view taken on the line 11—11 of Figure 3.

Figure 12 is a front elevational view of a delivery door and associated electrical control switches.

Figure 13 is an enlarged front elevational view, taken on an enlarged scale, showing the lower door switch.

Figure 14 is a horizontal section taken on an enlarged scale through the driving motor and gear assembly units.

Figure 15 is a longitudinal vertical section taken on the line 15—15 in Figure 14 through the gear assembly unit.

Figure 16 is a similar view taken on the line 16—16 of Figure 14 showing the conveyor driving motor unit.

Figure 17 is a fragmentary section of a detail of an adjusting set screw.

Figure 18 is a fragmentary vertical section

through a portion of the motor unit showing the pawl and ratchet mechanism.

Figure 19 is a similar view showing the pawl slot in the motor casing wall.

Figure 20 is also a fragmentary vertical section through a portion of the motor unit showing the locking dog.

Figure 21 is a perspective view, with parts broken away and parts shown in section, of the motor unit.

Figures 22 and 23 are inner face views of the two sections of the motor casing.

Figures 24 and 25 are similar views of the two sections of the gear assembly housing.

Figure 26 is a cross section through one section of the conveyor showing the ejector bars squeezing the ice cube from the container.

Referring more particularly to the drawings 25 designates a wall of a domestic or other refrigerator or housing in which the machine is contained either by incorporation in the original manufacture of the refrigerator or housing or by subsequent installation of the machine as a unit in the existing construction; and 26 indicates a tank or reservoir for precooled supply of water. The water in the tank 26 may be precooled by virtue of its inclusion in the refrigerating space of the refrigerator, or in the case of an unrefrigerated housing, such water may be precooled by a refrigerating coil 27 extending about or in other refrigerating relationship to the tank 26.

Adjacent the water supply tank 26 is a measuring dispensing chamber 28 which communicates with the main tank 26 through ports 29 and 30 in adjacent but spaced walls 31 and 32 of the tank 26 and chamber 28 respectively. In the space between the walls a vertically reciprocating valve 33 is fitted having a cross port 34 adapted in the lowered position to register with the ports 29 and 30. The port 30 is deeper vertically than the companion port 29 and is opened in the upper position of the valve 33 to a discharge nozzle 35 by means of a removed lower corner section 36 of the valve 33.

The valve 33 is biased to its upper position by a coil spring 37 mounted in the refrigerator housing 25 and connected to the armature 38 of the solenoid 39. A non-magnetic shaft 40 extends through the solenoid 39 and connects the armature 38 with the valve 33 which valve is also of non-magnetic material.

The spring 37 by contraction tends to lift the valve 33 to the position where its cross port 34 is masked by the blank walls 31 and 32 and with the lower removed section 36 setting up communication between the measuring chamber 28 and the discharge nozzle 35. When the solenoid 39 is energized the armature 38 is sucked inwardly, that is downwardly, carrying the valve 33 to its lower position in which the discharge nozzle 35 is plugged by the lower portion of the valve and the cross port 34 of the valve aligns horizontally with the ports 29, 30, thus setting up a communication between the main precooled water tank 26 and the measuring chamber 28, whereby a predetermined volume of the precooled water may be transferred from the tank 26 to the chamber 28 preparatory to its delivery in the raised position of the valve 33 through the discharge nozzle 35 to cups or other containers 41 carried upon a conveyor and passing in sequence beneath the discharge nozzle 35.

The conveyor carrying the ice cube containers 41 may be so constructed as to support a single line of such containers 41 in an endless path, or

a plurality of rows of such containers 41. In the single embodiment of the invention illustrated in the drawings, two parallel rows of the containers 41 are illustrated by way of example which provides for delivery of two cubes of ice in one delivery operation. The conveyors may be made of any suitable material in any appropriate form and preferably comprise endless chains 42 and 43 which are trained over pairs of toothed sprockets 44 and 45. Where a second row of ice cube containers 41 are provided a third endless chain 46 is provided together with additional sprockets to engage the end portions of the same; it being understood that in this case the intermediate chain 43 serves to support the containers 41 of both endless rows.

The containers 41 as shown in Figure 4 are supported across the chains 42, 43 and 43, 46 in any appropriate manner. Preferably conveyor webs 20 47 and 48 of rubber, rubber composition, or other elastic or resilient material is stretched across between the chains or belts 42, 43 and 43, 46. In practice the chains or belts 42, 43 and 46 may be moulded with the elastic or resilient compositions of the webs 47, 48 and the containers 41 into a single integral structure. The ice cube containers 41 are suspended from these webs 47 and 48 and are made from rubber, rubber composition or other elastic or resilient material. 30 Such containers are in the form of inverted pyramids or inverted cones with the apexes removed and replaced by rounded bottoms 49, as shown in Figure 5, 6 and 7. These rounded bottoms are concave on the interiors of the receptacles and 35 convex outwardly. The side and end walls of the containers 41 flare toward their open ends. In other words cross sectionally the containers 41 are larger at their open ends and progressively decrease in cross sectional area toward their 40 closed rounded bottom walls 49. The relationship between the containers 41 and their supporting conveyor webs 47, 48 is such that the resilient bottom convex walls 49 are suspended between the chains or belts and are positioned to contact the 45 mutually convex surfaces of ejection wheels 50 and 51 which are mounted in conjunction with the sprockets 45 at the discharge end of the conveyor. The ejection wheels 50, 51, as shown in Figure 11, exert on the convex bottoms 49 a radial outward thrust placing a forceful pressure on the 50 convex bottom surfaces 49 of the containers 41 and upon the ice cubes 52 contained therein. This pressure forces the normally convex bottom 55 walls 49 of the elastic ice cube containers 41 upward and into a concave position. The ice cubes 52 not being flexible or elastic like the container 41 are forced outward relatively to such containers 41. As the ice cube moves outwardly it is of necessity loosened from all side walls of the 60 ice cube containers 41 due to the pyramidal or conical construction of such walls of the ice cube containers.

The ejection wheels 50 and 51 may be mounted upon a shaft 53 at the ejection end of the machine. At the ejection end of the machine are mounted pairs of stationary ejector bars 54, 55, 56 and 57 with rounded or curved edges presented to the side walls of the elastic containers 41. These ejector bars 54, 55, 56 and 57 are approximately tangent to the surface of the ejection wheels 50, 51 and at their upper inner portions these ejector bars 54, 55, 56 and 57 are slightly tapered to present wide mouths into which the elastic containers 41 move incident to the travel 70 of the conveyor belt. As the elastic containers 41

descend between these pairs of ejection bars the side walls of the containers are progressively collapsed or pinched slightly toward one another at a point beginning approximately at the bases of the containers 41 and at an initial point approximately inwardly of the convex outer bottom surfaces of the ice cubes 52. As the cube containers progress in their travel around the ejection wheel 50 and 51, the pressure exerted by the ejection bars 54, 55, 56 and 57, due to their being positioned tangent to the arc of the ejection wheels 50 and 51, is applied progressively along the entire lateral sides of each cube container, beginning at the base and eventually extending to the mouth of each container as it finally passes completely through the ejection bars. This pressure acts to force and guide the ice cubes out of the containers 41 and into the delivery chute 60.

These ejection bars 54, 55, 56, 57 are carried in any appropriate manner for instance by a part of the framework 58 which may also act as a support for refrigerating coils 59.

A delivery chute 60 is positioned with its upper end below and forwardly of the ejector bars 54, 55 and 56, 57 in position to receive the ice cubes 52 from the receptacles 41. In the chute 60 is a trap 61 mounted on the spring hinge 62 which tends to maintain the trap or gate in the upper closed position thus minimizing undesirable circulation of air in the freezing chamber. The load of the spring on the hinge 62 is such that the trap 61 will yield to the weight of an ice cube 52 opening to permit the ice cube to fall by the force of gravity. The chute 60 delivers the ice cubes 52 to a delivery opening 63 in the door or other wall of the refrigerator case 25 and a drinking glass or other receptacle may be held beneath this delivery opening 63 to receive the ice.

The delivery opening is opened and closed by a vertically sliding door 64 mounted to slide in a channel or other guides 65 mounted in the refrigerator wall or door 25. This door may be conveniently lifted by a handle 66. Projecting into the path of the door at one side and at the lower portion of the door frame 65 is a lever 67 pivoted at 68 in the refrigerator structure 25 and having an inclined wall 69 disposed in the path of the door 64 to require the lever 67 to swing outwardly when the door is slid down to a closed position. The lever 67 is connected to a rod 70 carrying an electrical contact bar 71 adapted to close against the contacts 72 and 73 in the circuit 74. The rod 70 is connected to an armature 75 of a relay 76. When the sliding door is returned to a lower closed position it causes the rod 70 upon which are mounted a series of corrugated bands, 150, to slide under a sprung dog 149. This sprung dog is mounted on the wall 25 of the refrigerator door and in conjunction with the corrugated bands, 150, serves the purpose of maintaining the bar 71 across the electrical contacts 72 and 73. Thus when the sliding door is raised and pressure is removed from the lever 67 the circuit 74 remains unbroken across contacts 72 and 73. With the sliding door in a raised position, and the dispensing machine functioning at the proper moment the circuit 94 becomes actuated, thereby moving the armature 75 of solenoid 76 in such a direction as to move the contact bar 71, through the rod 70, away from the contacts 72 and 73 thereby opening circuit 74. This type of relay is generally known as a reset relay and the sliding door in returning to its closed position accomplishes the resetting of the contacts 72 and 73.

Projecting into the upper portion of the door 75

frame is a wedge-shaped lever 77 pivoted at 78 so as to be swung outwardly of the door frame on engagement by the upwardly sliding door 64.

To this lever is pivoted a rod 79 having affixed thereon a collar 80 engaged by a coil spring 81 which abuts against a guide 86 through which the rod 79 slides. The rod 79 carries an electrical contact bar 82 adapted to close against the spaced electrical contacts 83 and 84 which are also in the circuit 74. The spring 81 normally maintains the bar 82 out of engagement with the contacts 83 and 84 and holds the circuit open at this point. The raising of the door 64 shifts the rod 79 to compress the spring 81 and close the bar 82 against the contacts 83 and 84.

Referring to the circuit diagram, the water dispensing solenoid 39 is in a circuit 85 which may be opened at the contacts 87 and 88 by movement of the electrical contact bar 89. This bar is under the control of a relay 90 in a circuit 91. This circuit 91 is open at the contacts 92 and 93 while the circuit 94 for the relay 76 is opened at the contact 95. The contacts 92 and 93 are very close together while the contact 95 is spaced substantially from the contact 93. All of these contacts 92, 93 and 95 are in substantial alignment to be all closed in succession by a slidable contact bar 96 mounted upon a sliding bar 97 which is a part of one form of motor for driving the conveyor in its step by step progressive movement. A solenoid 98 is also a part of this motor; this solenoid being included in the circuit 74.

Although an electric motor or other suitable motor may be employed for the purpose it is preferred that the type of motor herein illustrated be used for intermittently driving the conveyor. This motor consists of the solenoid 98 having the armature 99 connected by a rod 100 to a floating pawl carrier 101 loosely mounted to rotate about the conveyor drive shaft 102 to which the sprockets 44 are keyed or otherwise affixed. The rod 100 has an end engaged in a radial slot 103 of the pawl carrier 101 and the rod itself plays through a cut-away portion 104 of the carrier in order to permit the rectilinear motion of the rod 100 imparting rotary motion to the pawl carrier 101.

The connection of the rod 100 is in the lower portion of the pawl carrier 101. Pivottally connected to its upper portion in the cut-away part 105 is a rod 106 connected to one end of a coil retractile spring 107 having its opposite end anchored at 108 to an appropriate part of the framework of the device.

The pawl carrier at its upper portion is provided with a radial slot 109 for receiving there through the pawl rod 110 which projects laterally beyond the rotary pawl carrier 101 for engagement with the teeth of a ratchet wheel 111 which is keyed or otherwise affixed to the conveyor drive shaft 102 alongside said rotary pawl carrier 101. The angular distance between the inclined and shouldered teeth of the ratchet wheel 111 is pre-selected to give the desired degree of linear movement to the conveyor at each actuation thereof.

The motor is contained in a case which in this instance may comprise two plates or sections 112 and 113. These case sections 112 and 113 are mounted between the chains 42, 43 and between the sprockets 44 of such claims. One section of the case fits against the ratchet wheel 111 and the other section of the case 112 has a thickened wall portion 114 in which is produced a slot 115 for receiving the end of the pawl rod 110 opposite that engaging the ratchet wheel 111. This

slot 115 has a curved wall portion 116 at its outer end leading to a downwardly offset portion 117.

The case sections 112 and 113 have apertures 118, 119 to fit about the conveyor drive shaft 102 and perforations 120, 121, 122 and 123 for receiving connecting bolts or fastenings 124 by which the two sections of the case are held together. Other perforations 125 and 126 in the case sections 112, 113 are for the purpose of receiving fastenings to hold the armature guide 127 in place.

A delay return mechanism for the pawl carrier 101 is provided which may consist in the instance shown of a reduction gear train comprising a gear wheel 128 fast on the conveyor drive shaft 102 and meshing with the comparatively smaller pinion 129 in turn driving a large gear wheel 130 meshing with a much smaller pinion 131 which in turn drives a larger gear wheel 132 meshing with a pinion 133 driving the flat fan 134 which when revolving sets up an air resistance which impedes the speed of the reduction gears. In this way the rate of speed of the conveyor belt is controlled. This gear train and fan are preferably contained in a speed control housing mounted in the space between the conveyor chains or belts 43 and 46. Such housing comprises the sections 135 and 136 having bearing apertures 137 and 138 to fit over the conveyor drive shaft and other bearing apertures 139 and 140 to receive the shafts 141, 142 and 143 of the gear assembly and fan. Perforations 144 and 145 are for the purpose of receiving bolts or other fastenings by which the two housing sections 135 and 136 are held together upon the reduction gear assembly.

A spring 145 is preferably coupled between the pawl rod 110 and the pawl carrier 101 tending to draw the pawl rod 110 radially inward to assure its engagement with the teeth of the ratchet 11. A pivoted spring-pressed dog 146 mounted horizontally adjacent but spaced from the securing point of the spring 145 but under the spring tension is also preferably engaged with the teeth of the ratchet wheel 111 to prevent reverse or retrograde rotation of the ratchet wheel 111 and its entrained parts including the conveyor drive shaft 102 and the conveyor and ice cube containers.

In operation, it will be noted from the circuit diagram that the contacts 72 and 73 for the relay 76 are normally closed by the electrical contact bar 71 when the machine has completed one cycle of its operation. When the door 64 is fully raised it encounters the lever 77 swinging the same outwardly and causing the closing of the normally open switch 82, 83 and 84 whereby the circuit is completed through the driving solenoid 98. The driving solenoid 98 when energized causes its armature 99 to move through the armature guide 127. As this armature 99 moves toward its solenoid 98, the rod 97 is moving therewith, shifting the electrical contact bar 96 into a position bridging all three contacts 92, 93 and 95. In bridging these three contacts the circuit 94 is closed through the contacts 92 and 95, thus energizing the relay 76 and causing the same to break the contacts 72, 73 and thereby opening the circuit 74 and deenergizing the driving conveyor solenoid 98.

However, while the drive solenoid 98 was still energized it has caused the armature 99 through the connecting rod 100 to move the floating pawl carrier 101 counter-clockwise through approximately 45°. This floating pawl carrier 101 revolves on the conveyor drive shaft 102 but is not

keyed to such drive shaft 102 and therefore does not entrain that drive shaft 102 to move in this counter-clockwise direction. In other words the locking dog 146 acting on the ratchet wheel 111 which is keyed to the conveyor drive shaft 102 prevents any counter-clockwise motion of the drive shaft 102 or conveyor. This counter-clockwise motion of the floating pawl carrier 101 distends the spring 107 and places the same under tension through the connecting rod 106.

As the floating pawl carrier 101 executes this counter-clockwise angular movement, the rod pawl 110 is rotated therewith approximately the distance of one tooth over the ratchet wheel 111 moving from the position *a* to the position *b* in Figure 20. The pawl spring 145 will yield to permit the rod pawl 110 to ride radially out on the inclined surface of the ratchet tooth between the positions *a* and *b* and after clearing the shoulder of the tooth such spring 145 will act to draw the pawl rod 110 radially inward to a position back of the shoulder of the tooth *b* in position to engage such shoulder and entrain the ratchet wheel 111 with the floating pawl carrier 101 on the return rotary movement of such floating pawl carrier 101.

When the circuit 74 to the driving solenoid 98 is broken, as previously explained, the tension on the spring 107 through the connecting rod 106 causes the floating pawl carrier 101 to return approximately 45° clockwise to its at-rest position shown in Figure 16. In returning clockwise the pawl rod 110 carries the ratchet wheel 111 therewith from position *b* to *a*, thus rotating the conveyor drive shaft 102 and moving the conveyor and its ice cube containers through a predetermined distance and the ejection wheels 50, 51 through a predetermined distance.

As the conveyor belt moves clockwise 45° around the ejection wheel 50 such conveyor belt carries with it the ice cube container 41 shown in position A in Figure 3 to move to position B. In doing so the convex surface of the ejection wheel 50 places a forceful pressure on the convex bottom 49 of the ice cube container 41 and the ice cube 52 contained therein. This action forces the normally convex bottom 49 of the resilient ice cube container 41 outwards and into a concave position. The ice cube 52, not being flexible like the container 41, is forced outwards. As the ice cube 52 moves outwards it is of necessity loosened from all sides of the ice cube container 41 due to the conical or pyramidal construction of the wall or walls of the ice cube container 41. As the ice cube 52 and cube container 41 shown in position C moves to position D in Figure 3, the cube container 41 passes between the stationary ejector bars 54, 55, 56 and 57 which exert a slight pinching pressure on the resilient wall or walls of the ice cube container 41. Such pressure forces and guides the ice cube 52 to fall free of its container 41 into the dispensing slot or chute 60.

As the ice cubes 52 fall onto the trap 61 their weight opens the trap 61 allowing such ice cubes to fall into the chute 60 which delivers them by the force of gravity to the dispensing aperture 63 shown in Figure 3. The dispensing trap 61 then returns to its at-rest upper position shown in Figure 3 caused by its spring hinge 62. The purpose of the trap 61 is to minimize undesirable circulation of air in the freezing chamber.

To return to the circuit diagram, as soon as the electrical contact bar 96 moves a short distance and thereafter for the entire forward and back-

ward movement of this contact bar 96, it maintains a closed circuit 91 through the relay 90. Relay 90 closes its contacts 87, 88 completing circuit 85 through the water dispensing solenoid 39. This is the circuit which operates the water dispensing valve 33 whose purpose is to inject the proper amount of water into each empty ice cube container 41 as it is required. When the water dispensing solenoid 39 is energized, as previously described, it causes the armature 38 to move downwards at the same time placing a tension on the spring 37. In this energized position the precooled water tank 26 becomes connected through valve port 34 with the dispensing chamber 28 which is normally empty of water but which immediately fills by gravity from the main tank 26, the air escaping through the air vent 147.

As the spring 107 retracts the electrical contact bar 96 back to the at-rest position where the bar disengages contact 93, circuit 91 is opened, deenergizing relay 90 and permitting the contact bar 89 to break the water dispensing solenoid circuit 85 at the contacts 87, 88. Thereupon the water valve 33 will be released to its spring 37 which will lift the valve to the position shown in Figure 2, closing the communication with the main tank 26 and opening the dispensing and measuring chamber 28 to the discharge nozzle 35 through which the measured quantity of water in the chamber 28 will be allowed to flow out into ice cube container 41 below. This completes the cycle of operations which in time, for example, may occupy approximately two seconds and is controlled by the speed reduction assembly contained in the case or housing 135, 136. This gear assembly places a load on the spring 107 of the motor thus slowing down the return or contraction of this spring 107. This causes the conveyor to move very slowly and results in a controlled movement of such conveyor.

Preferably the motor case and the gear assembly housing will be sealed against moisture and air. Such adjustment as may be necessary to govern the distance that the pall carrier moves during each individual cycle of its operation may be made by a set screw 148 the head of which screw is available on the outside of the motor housing.

A refrigerator or other structure containing an ice cube dispensing machine according to the present invention has many advantages over the conventional refrigerator. For instance as a matter of saving time, one or more cubes may be obtained in a matter of seconds; greater convenience is realized because there are no ice trays to break loose from a freezing chamber, no wasting and splashing of water in the sink to loosen ice cubes from trays and no juggling and spilling of a tray full of water in carrying same back to the refrigerator; greater economy results because when only a few cubes are desired it is not necessary to remove a tray full of cubes melting a portion of them, less defrosting due to less opening of the main door, better preservation of food because of less defrosting, less loss of energy due to less loss of refrigerated air together with less unnecessary cube meltage, less space required for the mechanism than for the normal complement of ice trays in conventional refrigerators and consequently more space available for other use.

While I have disclosed herein the best form of the invention known to me at the present time, I desire it to be understood that I reserve

the right to make changes and modifications in the herein described embodiment of the invention provided such changes fall within the scope of the following claims.

5. What is claimed is:

1. An ice cube dispensing machine comprising a conveyor, means for imparting movement to said conveyor, ice cube containers carried by and movable with said conveyor and of elastic or resilient material, and ejecting means disposed in the path of the side walls of the containers for exerting an inwardly squeezing movement on the elastic or resilient side walls to eject the ice cubes therefrom.

15 2. An ice cube dispensing machine as claimed in claim 1 characterized by the fact that said means comprises stationary ejector bars having rounded inner corner portions to guide the sides of the elastic containers into the bars.

3. An ice cube dispensing machine comprising a conveyor, elastic containers for ice cubes having outwardly convex bottoms and outwardly flaring walls, and a dislodging wheel with a convex surface over which said convex bottoms are moved in the course of movement of the conveyor to press upon the convex bottoms and the ice cubes contained therein to dislodge the ice cubes from the outwardly flaring walls of the containers, and ejecting means positioned relatively to the conveyor to pinch the walls of the elastic containers at or about the bottom portions thereof at a point back of the dislodged cubes to eject the cubes from the containers.

35 4. An ice cube dispensing machine as claimed in claim 3 in which the bottoms are internally concave to impart a convex formation to the inner ends of the ice cubes to enable a camming action by the ejector means beneath the ice cubes in the pinching action of the walls of the elastic containers, said camming action occurring as the cube containers move through and away from the ejector means in its travel around a dislodging wheel.

45 5. An ice cube dispensing machine comprising an endless conveyor, means for imparting movement to said conveyor, ice cube containers on and moving with said conveyor, means for ejecting the cubes from the containers, a delivery chute positioned to receive the ejected cubes from the 50 containers, and a normally closed trap in said delivery chute openable automatically by weight of an ice cube.

55 6. A device for delivering water in measured quantities comprising a main tank, a measuring chamber in position to receive water from the main tank by gravity flow and having an outlet, a valve for opening the communication between the tank and chamber and for opening and closing said outlet biased to a position in which the 60 outlet is open and communication closed between the tank and chamber, and means for shifting said valve to a position closing the outlet and opening the communication between tank and chamber.

65 7. A device as claimed in claim 6 characterized by the fact that a spring moves the valve to one position and a solenoid moves the valve to its opposite position, and means for energizing said solenoid, and with means for precooling the water.

8. An ice cube dispensing machine comprising a conveyor, containers for ice cubes on said conveyor, means for ejecting the cubes from the containers, and a motor for intermittently moving 75 said conveyor comprising a drive sprocket shaft

for said conveyor, a ratchet wheel affixed to said shaft, a pawl engaged with said ratchet wheel, a floating pawl carrier on said shaft beside said ratchet wheel, a solenoid connected to rock said pawl carrier in one direction, and a spring connected to the pawl carrier to be placed under tension on the solenoid movement of said pawl carrier to return the pawl carrier to at-rest position when the solenoid is deenergized.

9. An ice cube dispensing machine as claimed in claim 8 characterized by the fact that the pawl has a rod portion moving in a curved slot of a fixed casing part to cause the pawl when rotated to move radially inward to engage back of a shoulder of a ratchet tooth.

10. An ice cube dispensing machine comprising an endless conveyor, containers for ice cubes on the conveyor, a water delivery device to the empty containers at one end portion of the conveyor, a freezing chamber enveloping a portion of the upper run of the conveyor and the containers thereon, means for ejecting from the containers the frozen cubes at the other end portion of the conveyor, a motor for driving the conveyor step by step, a solenoid for actuating said motor, a second solenoid for actuating said water delivery device, relays for controlling the closing of the circuits through said solenoids, a delivery opening positioned to receive the ejected ice cubes from the containers, a door for such opening and switches positioned to be operated by said door in the opening and closing movements thereof and coupled to the circuits of the relays for starting and arresting the operation of the machine.

11. An ice cube dispensing machine as claimed in claim 10 characterized by the fact that said

motor solenoid when energized shifts an electrical contact bar into engagement with contacts for closing circuits through both relays, the contact bar for the relay of the motor solenoid being spaced remotely from the other contacts whereby such relay circuit is promptly opened on the return movement of the contact bar after deenergizing the motor solenoid but the relay circuit of the water delivery solenoid is maintained closed through the major movement of the contact bar in both directions of its movement.

12. An ice cube dispensing machine according to claim 11 characterized by the fact that said motor solenoid cocks a ratchet mechanism and stretches a return spring for actuating the ratchet mechanism to advance the conveyor, with means to slow the return contracting movement of the spring.

13. An ice cube dispensing machine according to claim 12 characterized by the fact that the means to slow the action of said spring comprises a reduction gear train and a flat fan driven thereby connected to a drive shaft of the conveyor.

25 FREDERICK A. HURLEY.
